UNITED STATES PATENT OFFICE.

MIKE LENKO, OF MINBURN, ALBERTA, CANADA.

DOOR-OPERATING DEVICE.

1,297,702.

Specification of Letters Patent. Patented Mar. 18, 1919.

Application filed July 19, 1918. Serial No. 245,626.

To all whom it may concern:

Be it known that I, MIKE LENKO, a subject of the Emperor of Austria, residing at Minburn, Province of Alberta, and Dominion of Canada, have invented certain new and useful Improvements in Door-Operating Devices, of which the following is a specification.

This invention relates to improvements 10 in means for operating doors suspended by rollers in such manner that they may slide in a horizontal plane.

The principal object of the invention is to provide a door, particularly applicable to 15 freight cars and the like, with means by which it may be readily and conveniently operated.

A further object is to provide means whereby the door may be maintained in an 20 adjusted position and prevented from premature closing.

These and other like objects are attained by the novel construction and combination 25 of parts hereinafter described and shown in the accompanying drawings, forming a material part of this disclosure, and in which:—

Figure 1 is a fragmentary side elevational view, showing a conventional type of freight 30 car and indicating the application of the invention.

Fig. 2 is an enlarged fragmentary side elevational view of the same.

Fig. 3 is a vertical sectional view taken on line 3—3 of Fig. 2.

Fig. 4 is a vertical sectional view taken on line 4—4 of Fig. 1.

Fig. 5 is an enlarged fragmentary sectional view, showing the door operating device and engaging means, and

Fig. 6 is a further enlarged transverse sectional view, taken on line 6—6 of Fig. 5.

In the drawings, a conventional type of freight car is indicated by the numeral 10, 45 resting upon the trucks 11 and provided with sliding doors 12, operable between the outer wall 14, and an inner partition or casing 16, the doors being suspended by cleats 18, bent and formed at their upper ends into 50 brackets in which are pivotally mounted, rollers 19, running upon a trackway 20.

Secured centrally on the door is a fending bar 22, adapted to make contact with the outer wall 14, similarly fixed fending 55 bars 23 being secured on the inner side of

the wall, contacting against the door as it is moved into an open position.

Secured to an eye 24 upon the inner edge of the sliding door 12, is the end of a cable 25, the same running over a pulley 26, journaled on a pin 27, set in the side of the car structure and at sufficient distance from the edge of the door to permit it to fully open without coming in contact with the pulley.

A similar pulley 28, journaled on the pin 29, is arranged relatively close to the door opening, the cable extending over the same, and then connected with an eye 30, formed with a horizontal sliding bar 32, mounted to move up and down within a groove 33, 70 formed in the casing parallel and contiguous to the recess in which the car door 12 slides.

The extending end of the bar has a looped operative handle 34, and a collar 35, normally drawn against the casing by the pull of a coiled compression spring 37, encircling the bar and abutting at one end against a collar 38, affixed to the bar 32, the outer end of the spring contacting with a globular 80 locking element 40, slideable on the bar, and engageable, due to the pressure of the spring, in any of the several vertically arranged, arcuate recesses 42 formed in the casing, thereby locking the cable and holding the door against closing.

It will be obvious that as the handle 34 is moved downward the bar 32 is depressed, causing the element 40 to slide rearwardly step by step over the raised edges of the adjacent recesses so as to bring the locking element 40 into engagement with the lower of the recesses, the door may be held adjustably open at any desired degree.

Having thus described my invention what I claim as new and desire to secure by Letters Patent, is.

1. In a door operating means, the combination with a sliding door, and a frame in which said door is engaged, of a cable secured to the inner edge of said door, a pulley over which the bight of said cable runs, a second pulley near the edge of said door, a horizontal bar having a handle extending through a slot formed in the frame of said door, a locking element slidably engaged upon said bar, means for pressing said locking element outwardly, and a plurality of depressions formed in the frame of said door in which said locking

100

105

110

element is adapted to engage, whereby said cable is held in different positions, corresponding with the position of the door.

2. In a door operating means, the combination with a sliding door, a frame in which said door operates, said frame having a vertical member, and containing a longitudinal slot adjacent to the inner edge of said door, a plurality of spaced recesses 10 in said frame, a cable engaged with the inner edge of said door, a pulley revolvably mounted remotely from said door, a second pulley mounted adjacent to said vertical member, said cable running over both of said

pulleys, a horizontal bar movable vertically in the slot of said vertical member, a handle on said bar by which it may be operated, a sliding stop element on said bar, means for pressing said stop element toward said handle, whereby it may be engaged in any of said recesses, said cable being secured to said bar whereby, as the latter element is depressed, said door is caused to open.

In testimony whereof I have affixed my 25 signature.

MIKE LENKO.
